UNITED STATES PATENT OFFICE.

EDWARD DOUBLE, OF LOS ANGELES, CALIFORNIA.

COMBINED ROTARY DRILLING NUT AND SLIPS.

1,143,257.

Specification of Letters Patent. Patented June 15, 1915.

Application filed June 8, 1914. Serial No. 843,707.

To all whom it may concern:

Be it known that I, EDWARD DOUBLE, a citizen of the United States, residing at Los Angeles, in the county of Los Angeles 5 and State of California, have invented a new and useful Combined Rotary Drilling Nut and Slips, of which the following is a specification.

This invention relates to a combined drilling nut and slips for rotary drilling.

Heretofore, so far as I am aware, in rotary drilling, the respective operations of rotating the stem and drill and of suspending the string, have been accomplished by 15 two different instrumentalities, a drill nut being employed for rotating the stem, and separate slips being employed for suspending the string. When rotating the stem, the nut has been placed in operative relation 20 between the table and stem to impart rotation from the table to the stem. In suspending the string the slips have been placed in substitution for the nut in operative relation between the table and string 25 to suspend the string. Thus, for two different operations, these two separate instrumentalities have been used interchangeably and either one in substitution for the other, according to the operations to be performed. 30 Where two separate instrumentalities are employed in such manner, it has been customary to lift the nut out of engagement with the table by means of the coupling in the string immediately below the nut which 35 forms an enlargement adapted for the purpose. When the nut was thus lifted out of place in the table the slips were inserted in lieu thereof. When the nut was used in engagement with the table, the slips had to 40 be removed and laid at one side.

With my invention the disadvantages of having two separate instrumentalities are avoided and a single element is provided that is so constructed that, when placed in 45 one position with respect to the stem and the table, it acts as a nut to revolve the stem, and, when placed in another position between the string and the table it acts as slips to engage the drill pipe and suspend the 50 string.

In carrying out my invention, I employ a member which on one side is formed to engage the string as a slip, and its other side is formed to engage the drilling stem to 55 produce rotation thereof, and either side is adapted to co-act with the table while the

other side is in engagement with the stem or the string. I preferably employ two such members. The sides of the members which co-act with the string as slips are so formed 60 as to also co-act with the table when their other sides are in relation with the drilling stem, and the sides which are adapted to co-act with the drilling stem are so constructed as to also co-act with the table when the 65 members are employed as slips to support the string.

The members are reversible with respect to each other so that their slip surfaces may be arranged toward each other for gripping 70 and suspending the string, or their nut surfaces may be placed toward each other in position for engaging the drilling stem.

Referring to the drawings, Figure 1 is a side elevation of the upper part of the rotary stem, showing the table in cross section with the device operating as a nut. Fig. 2 is a view, similar to Fig. 1, showing the device acting as slips. Fig. 3 is a plan view of the table as arranged in Fig. 1. Fig. 4 is a view, similar to Fig. 3, showing the table as arranged in Fig. 2. Fig. 5 is a perspective view of a member, looking toward the nut side. Fig. 6 is a perspective view of a member, looking toward the slip side. 85 Fig. 7 is a perspective view of one of the members of the split bushing.

1 designates the drilling stem which has one or more faces adapted to co-act with the nut to be described for producing the 90 rotative movement of the stem and the string, the stem preferably being square in cross section.

2 designates the lower portion of the string consisting of the usual drilling pipe 95 which is connected with the drilling stem 1 by a coupling 3.

4 designates the rotary table, operated in well known manner by bevel gear 5 and bevel pinion 6. The table 4 is recessed at 100 the center to receive a split bushing, consisting of two members 7, which are provided with shoulders 8 which take against similar shoulders 9 on the table, and the outer portions of the members 7 below the 105 shoulders 8 are round, while above the shoulders 8 they are square, that is to say, the two members together form a square, as clearly shown in Figs. 3 and 4. Each of the members 7 is also provided with a vertical notch 10, the back wall 11 of which is inclined, and with an inner flange 12; hand-

holds 13 are preferably provided on the members so that they may be easily lifted and withdrawn. Each of the members is also provided with a rabbet 14, so that when 5 the two members are in position a slot 15 is provided on opposite sides, which enables the passage of a fish tail bit without withdrawing the split bushing. The combined nut and slips, as herein shown, are formed 10 of two segmental members 16, each having a longitudinal groove 17, the bottom of which is parallel with the face in which it is formed. On the other side the member is formed with a concave groove 18, which is 15 provided with transverse ribs or teeth 19, the groove and face in which it is formed being at an angle to the opposite face. For convenience of description I will refer to the inclined face having the teeth as the slip 20 face, and the other face as the nut face. Either member is also preferably provided with suitable handholds 20 for withdrawing it. On the nut face the wall on either side of the groove 17 forms flanges 21, and on 25 the slip face flanges 22 are formed.

When the members are to be used as a nut, as in Fig. 1, they are inserted in the split bushing, with the flanges 21 touching each other, and the flanges 22 in contact 30 with the inclined back wall 11 of the associated member of the split bushing. When thus in position, the two grooves 17 form a nut, square in cross section, as clearly shown in Fig. 3, which nut engages the drilling 35 stem 1 and acts to revolve the same as the table revolves. When the members are to be used as slips, they are lifted out, reversed, and reinserted, as shown in Fig. 2, with the flanges 21 resting against the walls of the 40 split bushing, and the teeth 19 of the slip faces bearing against the drilling pipe 2 and biting the same in such a manner as to support the string. The gripping effect of the teeth 19 is produced by weight of the string 45 acting downwardly on the wedge-shaped members and forcing their teeth firmly into the drilling pipe. When the members are in use as slips, with their teeth 19 in contact with the drilling pipe, the teeth of both 50 members are parallel. When the members are used as nuts, the flange 12 forms a positive support for the members, preventing them from dropping through or from wedging 55 the string.

55 What I claim is:

1. In combination with a rotary string, a rotary table, a plurality of members rotated by the table, each of said members being provided with means on one surface for holding the string against longitudinal movement, and with means on another surface for imparting rotation to the string when the table is rotated.
2. In combination with a rotating table 65 and string, a plurality of members rotated

by the table, each of said members having a series of teeth on one face adapted to grip the string and hold the same from longitudinal movement, and having another face formed with a flat surface to engage the flat 70 face of the stem of the string and impart rotation thereto.

3. In combination with a rotary table and string, a plurality of members reversibly mounted with respect to the table, each of 75 said members being provided with means for gripping the string to suspend the string, and with means to rotate the string.

4. In combination with a rotating table and string, a plurality of wedge shaped 80 members, each of said members being provided with means for supporting the string against longitudinal movement, and with means for rotating the string, said table having inclined supporting means for supporting 85 said wedge shaped members.

5. In combination with a rotating table and string, members reversibly mounted on the table, and each provided with a face having a series of teeth for gripping the 90 string to suspend the string and provided with another face having a flat surface for engaging the flattened surface of the stem of the string for rotating the string.

6. In combination with a rotating table 95 and string, a plurality of members reversibly mounted on the table, each of said members provided with a concave surface having a series of transverse corrugations from the teeth adapted to engage and suspend the 100 string, each of said members having a longitudinal groove formed in the opposite face adapted when the member is reversed to engage the stem of the string to rotate the same.

7. In combination with a rotating table and string, a bushing in the table formed with a tapering inner wall, and members reversibly mounted in said bushing and fitting between said wall and string and each 110 provided on one face with means for supporting the string and on another face with means for rotating the string.

8. In combination with a rotary table and string, a split bushing in the table, the members of the bushing having inclined inner walls, a plurality of wedge shaped members fitting against the inclined inner walls of the bushing and against the string, each of said members having a face with teeth for gripping the string to suspend the same and having another face with a flattened surface to engage the stem of the string to rotate the same.

9. In combination with a rotary table and string, a split bushing in the table, the members of the bushing having inclined inner walls, a plurality of wedge shaped members fitting against the inclined inner walls of the bushing and against the string, each of said 125 members having a face with teeth for gripping the string to suspend the same and having another face with a flattened surface to engage the stem of the string to rotate the same.

members having a face with teeth for gripping the string to suspend the same and having another face with a flattened surface to engage the stem of the string to rotate the same, the first mentioned face of each member having flanges adapted to rest against the inclined face of the bushing when the opposite face is in engagement with the stem, and the second mentioned face of the member being provided with flanges adapted to rest against the inclined face of the bushing when the opposite face is engaging the string to suspend the same.

10. In combination with a rotary table and string, a split bushing in the table, the members of the bushing having inclined inner walls, a plurality of wedge shaped members fitting against the inclined inner walls of the bushing and against the string, each of said members having a face with teeth for gripping the string to suspend the same and having another face with a flattened surface to engage the stem of the string to rotate the same, said bushing having an inward flange for supporting said members when they are engaging the stem to rotate the string.

11. In combination with a rotary table and

string, a split bushing in the table, the members of the bushing having inclined inner walls, a plurality of wedge shaped members fitting against the inclined inner walls of the bushing and against the string, each of said members having a face with teeth for gripping the string to suspend the same and having another face with a flattened surface to engage the stem of the string to rotate the same, the first mentioned face of each member having flanges adapted to rest against the inclined face of the bushing when the opposite face is in engagement with the stem, and the second mentioned face of the member being provided with flanges adapted to rest against the inclined face of the bushing when the opposite face is engaging the string to suspend the same, said bushing having longitudinal slots to permit the passage of a fish-tail bit.

In testimony whereof I have hereunto set my hand at Los Angeles, California, this 30 day of May 1914.

EDWARD DOUBLE.
